UNITED STATES PATENT OFFICE

JOHN HAMILTON GILLIS, OF GAINESVILLE, TEXAS

MOP HOLDER

Application filed November 30, 1928. Serial No. 322,779.

This invention relates to mops and more particularly to holders for connecting the mop head with the handle.

A primary object of the invention is to provide simple and efficient means whereby a mop head or mopping material may be easily inserted or removed and when connected with the handle or stick it will spread out over the ends of the stick and the connecting parts to prevent their contact with the floors or furniture.

Another object is to so connect the mop head with the stick that the mopping material may be easily washed and wrung out keeping it sanitary and adapting it to be easily wrung out either by hand or by means of a mop wringer.

Another object is to so construct such a holder that the locking spring therefor will be protected so that a comparatively thin spring may be used for this purpose and yet be thoroughly effective.

In carrying out these objects, the invention is susceptible of a wide range of modification without departing from the spirit or sacrificing any of the advantages of the claimed invention; there being shown in the drawings for illustrative purposes a preferred and practical form, in which:

30 Figure 1 represents a side elevation of a portion of a mop stick and head with this improved holder shown applied;

Fig. 2 is a similar view taken in a plane at right angles to Fig. 1;

35 Fig. 3 is a transverse section taken on the line 3—3 of Fig. 1; and

Fig. 4 is a detail perspective view of the locking spring detached.

In the embodiment illustrated a portion 40 of a mop stick or handle 1 is shown which is made round as is ordinarily done and to the lower end of which is designed to be connected a mop head 2 composed of any suitable mopping material.

45 The connector or holder 10 which is designed for uniting the head 2 to the handle 1 is shown substantially U-shaped or in the form of an open ring 11 construction or heavy wire of a size which will not easily bend or be sprung out of shape when in use,

and which has the ends thereof extended laterally parallel with each other to form legs 12 and 13 which are designed to straddle the lower end of the mop stick 1 and be connected therewith in a manner presently to be described.

55 The ring 11 is made of a size suitable to hold the mop head or mopping material to be used in connection therewith and the legs are designed when the device is applied to 60 slip longitudinally through screw eyes 3 which are inserted in diametrically opposite sides of the handle 1, two being preferably arranged at each side and in longitudinally spaced relation as is shown clearly in Fig. 1. 65 These eyes form guiding and retaining means for the legs 12 and 13 of the holder. One of the legs, the one numbered 13, being 70 here shown provided on its inner face with a series of ratchet teeth 14 designed to co-act with a plate spring 15 secured to the handle 1 for locking the holder to the handle. This plate spring 15 is attached to the handle preferably by means of a screw 16 and has one end notched as is shown at 17 to fit over 75 and interlockingly engage with one of the screw eyes 3 whereby the spring is secured to the handle at one end with its opposite end left free and bent laterally outward as shown at 18 to form a dog or pawl for cooperative 80 engagement with the teeth 14 of the leg 13. This spring 15 is inserted under a band 19 slidably mounted on the handle 1 and which is designed to control the tension of the spring it being obvious of course that this 85 band is moved longitudinally on the stick so that the tooth engaging end thereof will be permitted to spring out or to be moved in according to the will of the operator.

90 To adapt the spring 15 to be properly applied to the handle the side face of the handle under the leg 13 is preferably cut away or flattened as shown clearly in Fig. 3 to adapt the spring to lay close against the handle.

95 In the use of this holder the mop head or mopping material is placed in the ring 11 with the ends of the material extending beyond the opposite sides of the ring. The legs 12 and 13 are then slipped forward through the eyes 3, dog 18 on spring 15 slipping over 100

the ratchet teeth 14 of leg 13 until the holder has been moved as far onto the handle as may be done by hand. Then the mopping material of the head 2 is spread out and the ring 11 engaged with the floor or other rigid support and downward pressure is exerted on the handle 1 which will cause the material of the mop head to be compressed tightly between the handle end and the ring 11 in 10 which position it will be held by locking the dog 18 with the leg 13. When this has been done the mop head is shaken out and a good round mop will be the result, which will be effectively held engaged with the handle and 15 the spring 15 will be fully protected by the leg 13 which overlies it.

When it is desired for any reason to remove the mopping material the band 19 is slipped rearwardly on the handle 1 to dis- 20 engage the spring dog 18 from the ratchet teeth of the holder and the holder may then be moved forwardly to remove the head 2 or to insert additional mopping material in the ring 11. As is clearly shown in Figs. 1 and 2 25 of the drawings when the head 2 is connected with the handle 1 in the manner above set forth it will spread out around the holder and fully cover both it and the handle end so that they will not contact with the floor 30 being mopped or with walls, moldings, or furniture during use.

This holder obviously may be very cheaply constructed so that it may be placed at the disposal of all house wives and cleaners at a 35 very nominal cost and which will outlast many mop heads.

Without further description it is thought that the features and advantages of the invention will be readily apparent to those 40 skilled in the art, and it will, of course, be understood that changes in the form, proportion and minor details of construction may be resorted to, without departing from the spirit of the invention or its scope as claimed.

45 I claim:

The combination with a mop stick; of a holder for connecting a mop head to the stick comprising a loop to carry the head and having parallel legs to straddle the stick, guid- 50 ing and retaining eyes carried by the stick in which the legs of said holder are adapted to slide, one of said legs having ratchet teeth on its inner face, a plate spring secured at one end to the stick and having its other end 55 curved outwardly to form a locking dog to engage the teeth of said leg, whereby the holder is locked to the stick, and a combined spring releasing and tensioning device slide- 60 ble on the stick over said plate spring to release the dog from the ratchet teeth and to vary the tension of the spring.

JOHN H. GILLIS.
